UNITED STATES PATENT OFFICE.

NATHAN BARNEY, OF BERGEN POINT, NEW JERSEY.

AUTOMATICALLY-DUMPING BOAT.

SPECIFICATION forming part of Letters Patent No. 226,960, dated April 27, 1880.

Application filed March 2, 1880. (Model.)

To all whom it may concern:

Be it known that I, NATHAN BARNEY, of Bergen Point, in the county of Hudson and State of New Jersey, have invented certain new and useful Improvements in Automatically-Dumping Boats; and I do hereby declare that the following is a full, clear, and exact description of the invention, which will enable others skilled in the art to which it appertains to make and use the same, reference being had to the accompanying drawings, and to the letters of reference marked thereon, which form a part of this specification.

The invention relates to an improved automatically-dumping boat; and it consists in the construction and arrangement of parts, as will be hereinafter more fully set forth.

In the annexed drawings, Figure 1 is a plan view. Fig. 2 is an end elevation with the bottom closed. Fig. 3 is a central vertical section with the bottom open, and Fig. 4 a similar view with the bottom closed.

In the drawings, A represents the platform or deck; B, the cross-pieces on the under side of the deck, to which the bottom is pivoted; C C, the divided bottom; D, the ends; E, cogs on the ends; F, sliding bolt; a, projections on bolt; b, rack on bolt; c, ears on end pieces to engage with projections a on bolt; d, rod; e, pinions secured on rod d and engaging with the racks b; f, bearings for the rod d.

The platform A is constructed in the form shown, the cross-pieces B strengthening the same, and their ends passing in slotted standards secured upon the side of the bottom C C and pivoted thereto, as shown, thereby allowing the bottom to open and close as desired. The upper portions of the end pieces are provided with cogs E, which, when the bottom is opened and closed, engage with each other and guide the parts in the proper position.

The rod d may have attached to it a permanent lever, or it may be square at certain portions to receive a wrench. When the bottom

is closed the ears c rest upon the projections a 45 and hold the parts together; and the bottom may also be held open in the same manner.

The operation of the device is as follows: When it is desired to dump the load the rod d is turned. The pinions thereon, engaging with the rack on the sliding bolt, draw the projections a from under the ears c and permit the load to pass through. If the load is not perfectly dumped, the bottom may be held open and the boat towed in that position until it is 55 perfectly free from its load. As soon as the boat is relieved from the load, or, if held open by the bolt, as soon as the bolt is drawn the bottom closes automatically and is secured by the bolt, when it is ready to receive another 60 load.

The advantages of this device are many. It greatly reduces the cost of labor, as one man can operate the device easily. Its simplicity and cheapness of construction are obvious, and 65 it is not liable to get out of repair. The boat may be provided with a bow, if desired.

Having thus fully described my invention, what I claim as new, and desire to secure by Letters Patent, is—

1. A dumping-boat having its bottom in two parts, pivoted on opposite sides of a suitable platform, and the ends provided with cogs, whereby the boat is opened longitudinally to dump the load, and is returned automatically 75 and accurately to its former position, substantially as and for the purpose set forth.

2. The platform A, cross-pieces B, having the bottom C C pivoted thereto, and the end pieces, D, having the cogs E, substantially as 80 and for the purpose set forth.

In testimony that I claim the foregoing as my own I have hereto affixed my signature in presence of two witnesses.

NATHAN BARNEY.
